UNITED STATES PATENT OFFICE.

OSWALD S. PULLIAM, OF NEW YORK, N. Y.

REAR-AXLE DRIVE FOR MOTOR-VEHICLES.

1,371,809.

Specification of Letters Patent.

Patented Mar. 15, 1921.

Application filed May 19, 1919. Serial No. 298,227.

To all whom it may concern:

Be it known that I, OSWALD S. PULLIAM, a citizen of the United States, and a resident of the city of New York, borough of Manhattan, in the county and State of New York, have invented a new and Improved Rear-Axle Drive for Motor-Vehicles, of which the following is a full, clear, and exact description.

10 The present invention relates to new and useful improvements in rear axle drives for motor vehicles, and has for its primary object to provide a device of this character which is adapted to take the place of the 15 ordinary differential commonly employed for this purpose.

A further object of the present invention is to provide means by which differential movement of the driving wheels of a motor 20 vehicle is obtained, and, at the same time, provision is made for positively locking both of said wheels directly with the power-transmitting element.

A still further object of the invention is 25 to so construct a device of this character that the positive locking thereof is obtained in either direction.

With the above and other objects in view, reference is had to the accompanying drawings in which—

Figure 1 is a top plan view of a motor vehicle rear construction;

Fig. 2 is a detail sectional view on the line 2—2 of Fig. 1;

35 Fig. 3 is a vertical sectional view on the line 3—3 of Fig. 2;

Fig. 4 is a longitudinal sectional view of a modified form of the invention;

40 Fig. 5 is a transverse sectional view on the line 5—5 of Fig. 4.

Referring more particularly to the drawings, the reference character 10 designates a bevel gear of the rear axle driving mechanism, and projecting from opposite sides of 45 the bevel gear 10 are stub shafts 11, each of which is provided with a spiral groove 12, the groove in one shaft extending in a direction opposite to that in the other shaft.

Surrounding each of the stub shafts 11 is 50 a sleeve 13, and said sleeves are divided intermediate of their ends by means of a partition 14. On the outer end of each of said sleeves and beyond the partition 14 thereof, is a shaft 15, and to these shafts 15 the rear 55 driving wheels of the motor vehicle are secured, said wheels being designated by the

reference character 16. Each of these shafts 15 is provided with a spiral groove 17, and said spiral groove extends in a direction opposite to the spiral groove of its adjacent 60 stub shaft 11.

Mounted within each of the sleeves 13 on opposite sides of its partition 14, are coil springs 18, there being two of said coil springs on each side of said partition. 65 Mounted between the adjacent ends of the coil springs 18, are keys 19, and said keys 19 are adapted to engage in the spiral grooves 12 and 17 for a purpose to be hereinafter described. As shown in Fig. 3, 70 these keys 19 comprise a substantially circular plate, from the peripheral edge of which projects a substantially rectangular member 19', which is adapted to lie within the spiral groove as hereinafter mentioned. 75

The operation of this form of the device is as follows: Power being transmitted to the bevel gear 10, the same is rotated in a forward direction. As the bevel gear 10 rotates, the keys 19 which operate in the 80 spiral grooves of the stub shafts 11, will be moved to place one of the springs 18 under compression, the spring 18 being compressed depending upon the direction of rotation of the gear 10. As the spring 18 becomes 85 completely compressed, the sleeves 13 will be rotated, and through the medium of the keys 19, in their outer extension, will place one of the springs in the outer section of the sleeve under compression. As this spring 90 continues to compress, and its limit of compression is reached, the shafts 15 of the driving wheels 16 will be rotated.

When the power is released from the bevel gear 10, the device is returned to its normal position by the exertion of the stored up energy in the springs 18, the sleeves 13 rotating about their respective shafts and stub shafts to permit of this operation.

In Fig. 4 is shown a modified form of the 100 invention and in this form the springs 18 are dispensed with. The bevel gear wheel 10 is provided on its opposite faces with stub shafts 20, each of which is provided with a continuous thread 21. Surrounding 105 the stub shafts 20, are sleeves 22, and slidably mounted in slots 23 in said sleeves 22, are keys 24.

In the form of the invention shown in Fig. 4, the elements 20 and 21 are the equivalent of the axles 15 in the preferred form 110 of the invention, the spring, however, in this

form having been removed in order that the keys 24 may lock positively instead of setting against a resilient action.

By this construction, it will be seen that 5 as the stub shafts 20 are rotated in either direction by means of the bevel gear 10, the keys 24 will be moved to the ends of their respective slots 23, and when the ends of said slots are reached, the sleeves will serve 10 to rotate the stub shafts 20 and communicate power to the driving wheels 16 of the motor vehicle.

Claims:

1. A device of the character described, 15 comprising a gear, a stub shaft projecting from opposite side faces of said gear, and each provided with a spiral groove, a sleeve surrounding each of said stub shafts, and adapted to receive the inner ends of the 20 rear axles, a plurality of coil springs carried by said sleeves, and means carried by said

sleeves and operating in said spiral grooves for placing said springs under compression as and for the purpose described.

2. A device of the character described, 25 comprising in combination with the rear axles of a motor vehicle, a gear wheel provided with oppositely disposed stub shafts provided with a thread, and means for resiliently connecting each of the oppositely 30 disposed stub shafts with its respective axle.

3. A device of the character described comprising a driven member provided on its opposite sides with spirally grooved stub shafts, a spirally grooved shaft in axial 35 alignment with each of said stub shafts, and means engaging the spiral groove of each of said stub shafts and the spiral groove of each of said axially aligned shafts for operatively connecting each stub shaft with its 40 respective axially aligned shaft.

OSWALD S. PULLIAM.
